DESIGN FOR A PHOTOGRAPHIC ILLUMINATOR

Stephen M. Tucker, Rochester, N. Y., assignor to Eastman Kodak Company, Rochester, N. Y., a corporation of New Jersey

Application September 23, 1941, Serial No. 103,458

Term of patent 14 years

To all whom it may concern:

Be it known that I, Stephen M. Tucker, a citizen of the United States, residing in Rochester, in the county of Monroe and State of New York, have invented a new, original, and ornamental Design for a Photographic Illuminator, of which the following is a specification, reference being had to the accompanying drawing, forming part thereof.

In the drawing:

Fig. 1 is a perspective view from the front right hand corner of a photographic illuminator showing my new design.

Fig. 2 is an elevational view of the left hand side of the same.

I claim:

The ornamental design for a photographic illuminator, as shown.

STEPHEN M. TUCKER.
